CLAIM

The ornamental design for a paper binder, as shown and described.

DESCRIPTION

FIG. 1 is a perspective view of a paper binder showing my new design;

FIG. 2 is a top plan view thereof;

FIG. 3 is a front view thereof;

FIG. 4 is a rear view thereof;

FIG. 5 is a left side view thereof;

FIG. 6 is a right side view thereof;

FIG. 7 is a bottom plan view thereof;

FIG. 8 is a magnified plan view showing a part taken along line 8—8 in FIG. 2;

FIG. 9 is a cross sectional view taken along line 9—9 in FIG. 8;

FIG. 10 is a cross sectional view taken along line 10—10 in FIG. 8;

FIG. 11 is a perspective view of the paper binder in a state that the paper binder is closed;

FIG. 12 is a perspective view of the paper binder in a state that a lever thereof is lifted up;

FIG. 13 is a top plan view of another embodiment of the paper binder;

FIG. 14 is a front view thereof;

FIG. 15 is a rear view thereof;

FIG. 16 is a left side view thereof;

FIG. 17 is a right side view thereof;

FIG. 18 is a perspective view of the paper binder shown in FIGS. 13-17 in a state that the paper binder is closed; and,

FIG. 19 is a perspective view of the paper binder shown in FIGS. 13-18 in a state that the paper binder is opened.
